UNITED STATES PATENT OFFICE.

JOSEPH HOMER, OF BOSTON, MASSACHUSETTS, ASSIGNOR TO CORINNE HOMER, OF BROOKLINE, MASSACHUSETTS.

DENTAL ARTICULATOR OR RELATOR.

Application filed June 6, 1923. Serial No. 643,730.

To all whom it may concern:

Be it known that I, JOSEPH HOMER, a citizen of the United States, and a resident of Boston, in the county of Suffolk and 5 State of Massachusetts, have invented a new and Improved Dental Articulator or Relator, of which the following is a full, clear, and exact description.

This invention relates to a dental articulator or relator and is related to my co-pending application, Serial No. 504,758, filed October 1, 1921, entitled "Dental articulator."

An object of the invention is to provide 15 an articulator having two movable jaws, one of which is normally fixed and the other of which is relatively movable with respect to the first, the connection between the movable member and its support being a particular 20 feature of the invention, permitting an especial movement or adjustment of the movable jaw or member not hitherto obtainable.

The invention is illustrated in the drawings, of which—

Figure 1 is a sectional view taken on the line 1—1 of Fig. 2;

Fig. 2 is a vertical section taken on the line 2—2 of Fig. 1; and

Fig. 3 is a front elevation of the device.

The form of the invention shown in the drawings is a preferred form, although it is understood that modifications in the construction and arrangement of the parts and 35 in the character of the materials used may be adopted without departing from the spirit of the invention.

In the drawings there is illustrated a dental articulator comprising a frame having 40 a fixed jaw 1 and a movable jaw 2, on which jaws are adapted to be mounted forms or molds of human jaws or gums on which a dentist mounts artificial teeth, and by reason of the permissible relative movement between the jaws can so align the teeth as to 45 give them their proper relative movement in cutting and chewing food. The fixed jaw 1 is provided at its rear end with pedestal elements 3 and 3^a pierced at their upper 50 ends and adapted to lie adjacent the similar pierced ends 4 and 5 of an upper movable frame member 6. This upper movable frame member 6 is provided with a hollow chamber 7 which, when the frame member 6 is 55 disposed in normal position, (shown in

Fig. 1) extends forwardly and horizontally parallel to the normal position of the fixed jaw 1. A pin 8, passing through the apertures above mentioned, pivotally connects the frame member 6 to the pedestal members 2 and 3.

The movable jaw 2, at its rear end, is provided with slots or holes such as 9 (see Fig. 1) or modifications, this rear end projecting normally into the chamber 7. Surrounding the rear end of the movable jaw 2 there is disposed a mass of plastic material 10 of any suitable character which will gradually harden while the movable jaw 2 is being moved in the same, thereby permitting a certain play or movement after hardening relative to the frame member 6 to which it is connected by this plastic medium. In other words, viewing the parts shown in Fig. 2, there is sufficient play between the movable jaw 2 and the frame member 6 to permit of local movement of the jaw 2 with respect to the frame 6 without moving the frame member 6. This will permit a movement of the mold or form 70 mounted on the jaw 2 which would not otherwise be possible, or by reducing the movement before the plastic material has hardened an adjustment is permitted of the movable jaw 2 in respect to the frame 6 75 holding them in rigid changed relation.

I provide a crossbar 11 extending between the pedestal members 2 and 3, and passing through this bar is a screw 12 which can be clamped in a fixed position by means 80 of a nut 13, the screw and its proper nut bearing against the lower edge or face of the frame member 6, permitting it to be adjusted and moved around its pivotal point to assume any desired position relative to 85 the fixed jaw 1. After being adjusted the screw can be fixed by means of the clamping or lock nut 13.

What I claim is:—

1. A dental articulator comprising fixed 100 and movable frame members, said movable frame member provided with a chamber, a jaw member having a portion adapted to extend into said chamber, and a plastic medium disposed in said chamber surrounding the end of said jaw member to connect it to said frame member while permitting a certain movement thereof relative to the frame member.

2. A dental articulator including a fixed 110

and a movable frame member, one of said members having a chamber formed therein, a jaw member having a portion projecting into said chamber, and a mass of plastic material disposed in said chamber around the portion of the jaw member projecting thereinto to connect the jaw member to the frame member.

3. A dental articulator which includes a fixed jaw, pedestal members on said jaw, a movable frame member pivoted to said

pedestal member, said movable frame member having a chamber disposed horizontally and with its open end extending forwardly when the frame member is in its normal position, a movable jaw member having a portion extending into said chamber, and a mass of plastic material disposed in said chamber surrounding the portion of the movable jaw extending thereinto. 15

JOSEPH HOMER.
